UNITED STATES PATENT OFFICE.

ALONZO E. RHOADES, OF HOPEDALE, MASSACHUSETTS, ASSIGNOR, BY MESNE ASSIGNMENTS, TO DRAPER CORPORATION, OF PORTLAND, MAINE, A CORPORATION OF MAINE.

AUTOMATICALLY-THREADING LOOM-SHUTTLE.

1,212,402.

Specification of Letters Patent. Patented Jan. 16, 1917.

Application filed October 12, 1915. Serial No. 55,392.

To all whom it may concern:

Be it known that I, ALONZO E. RHOADES, a resident of Hopedale, in the county of Worcester and State of Massachusetts, have 5 invented a new and Improved Automatically-Threading Loom-Shuttle of which the following is a specification.

In an accompanying application for Letters Patent of the United States, filed October 11, 1915, Serial No. 55,330, I have described an automatic weft replenishing loom wherein the weft carriers are held in the magazine with their tips toward the warp. This involves a shuttle having its eye and 10 threading end toward the warp when at the replenishing side of the loom. It is obvious that such shuttle can not be automatically threaded in the same manner as in well known weft replenishing looms wherein the 15 threading end toward the warp when at the replenishing side of the loom. It is obvious that such shuttle can not be automatically threaded in the same manner as in well known weft replenishing looms wherein the 20 threading and eye end of the shuttle is near the picker when in the shuttle box at the replenishing side of the loom, as exemplified, for example, in United States Letters Patent of Northrop No. 529,940, November 27, 25 1894. A novel shuttle is thus required, and such novel shuttle constitutes the present invention.

The new shuttle is illustrated in the accompanying drawings, wherein—

30 Figure 1, is a plan view of the threading end of the shuttle. Fig. 2, is a vertical longitudinal section in the plane indicated by the line 2—2 in Fig. 1. Fig. 3, is a cross-section in the plane indicated by the line 3—3 in Fig. 1. Fig. 4, is a cross-section in the plane indicated by the line 4—4 in Fig. 1.

The shuttle A, has its eye a, at its end which is near the warp when occupying the 40 shuttle box at the replenishing side of the loom. That is to say, the eye is located at the front and left hand end of the shuttle, namely, the end of the shuttle which is the advancing end during the first flight of the 45 shuttle after replenishment, so that the shuttle may be called "left-handed."

Fig. 1, shows the tip end of a bobbin B, in the chamber C, of the shuttle. There is shown a sheet metal threadder D, which is similar 50 to that set forth in United States Letters Patent of Stimpson No. 933,497, September 27, 1909, excepting for the supplementary hook E, the recess F, in the rear wall G, of the sheet metal threadder, and the fore- 55 shortening of the guard H.

The supplementary hook E, is located at the entrance end of the threading passage I, of the threadder. In the illustrated sheet metal construction the hook is integral with the front wall J, of the sheet metal threadder 60 and is bent first rearwardly from the inner edge of said wall and thence both forwardly in the direction of the first flight of the shuttle when replenished and rearwardly, so that it extends diagonally across the entrance to the thread passage of the threadder. The upper edge b, of the supplementary hook extends downwardly from front to rear. The lower edge c, of the supplementary hook is sufficiently far above the upturned inner end K, of the sheet metal threadder and above the tension pad L, (when employed) to afford ample room for the passage of the thread. The extreme forward and rear point d, of the supplementary 65 hook enters partly within the recess F, in the rear wall of the threadder but leaving room for the passage of the thread between the floor of the recess and the point d, of the supplementary hook. 70

The inner edge e, of the guard H, which overhangs the beak M, of the threadder extends laterally of the shuttle above the threading passage I, and between the transverse plane of the eye a, of the shuttle and 85 the neighboring tip N.

As explained in the aforesaid co-pending application, the supplementary threading is effected by the aid of a thread placer which carries the weft end of the incoming weft 90 carrier into the space O, between the end of the weft carrier and the threadder and below the supplementary hook E. At the same time a thread finger carries the thread of the incoming weft carrier downwardly 95 close to the top of the shuttle forward of the inner edge e, of the guard H. As a consequence the thread of the incoming weft carrier is laid in a position closely approximating the line P—P in Fig. 2. This line 100 extends lengthwise of the shuttle and back of the center line of the shuttle. Accordingly, the thread placer and thread finger carry the thread downwardly against the upper downwardly and rearwardly inclined 105 edge b, of the supplementary hook E, and toward the rear wall G, of the threadder. The thread as it is pressed downwardly by the thread placer and thread finger rides readily over the point d, of the supplemen- 110

tary hook, passing through the recess F, in the rear wall of the shuttle. The thread is thus placed in the threading passage I, below the supplementary hook. The thread 5 cannot spring outwardly and above the supplementary hook E, because the supplementary hook passes entirely across the threading passage I, and into the recess F, in the rear wall of the sheet metal thresher and the application of some force 10 is required to pass a thread into the said recess and around the point of the supplementary hook. By the action of the thread placer and finger the thread is thus passed 15 below the supplementary hook on its way from the inserted weft carrier to the weft end holder. When, then, the shuttle makes its first flight through the shed with its eye end in advance, the thread reeves around 20 the base f, of the supplementary hook which serves as an initial threading device. On the second or return flight of the shuttle back to the replenishing side of the loom the thread is drawn between the guard H, and the beak M, this action being insured by the 25 supplementary hook which holds the thread down in the thread passage I. Then during the third flight of the shuttle following replenishing, as the shuttle travels with its 30 eye end forward, the thread passes beneath the beak M, and into the side eye a, in the same manner as in the shuttle of said Northrop patent when used in the former weft replenishing looms of the type illustrated, 35 for example, in the aforesaid Northrop Patent No. 529,940.

Owing to the circumstance that the hook E, is at the rear of the thresher, and the edge e, of the guard H, is forward of the 40 eye a, ample space is afforded for the thread to occupy the path indicated at P—P in Fig. 2, which brings it below the hook.

A flaring entrance mouth Q, for the thread exists between the hook E, and the 45 rear wall G, which facilitates the direction of the thread to the point of the hook.

The hook serves as a guard to aid in preventing the accidental escape of the fully threaded weft.

50 I claim—

1. A left-handed loom shuttle having the eye in the front side of the left-hand end and having a sheet metal thresher with a front wall J; a rear wall G; a beak M; a 55 guard H, with a transversely extending inner edge e between the transverse plane of said passage, and said hook constituting the engaging means around which the thread reeves as it passes from the weft carrier on the first flight of the replenished shuttle.

60 2. A left-handed loom shuttle having the eye in the front side of the left-hand end and having a sheet metal thresher with a front wall J; a rear wall G; a beak M; a guard H, with a transversely extending inner edge e between the transverse plane of the shuttle eye and the neighboring tip of the shuttle; a recess F, in the rear wall G; and a supplementary hook E, formed integrally with the front wall of the thresher at the inner edge thereof and bent rearwardly and also forwardly in the direction of the first flight of the shuttle when replenished with its point extending into the 65 said recess F, thereby providing a flaring

entrance Q, for the thread, and the upper edge of said supplementary hook extending downward from front to rear and said hook extending above the threading passage I, in the thresher, said hook constituting the 70 sole engaging means for the thread as it passes from the weft carrier on the first flight of the replenished shuttle.

2. A left-handed loom shuttle having a threading passage and an eye in the front side of the left-hand end; a guard overhanging the outer end of said passage with its transversely extending inner edge between the plane of the shuttle eye and the neighboring tip of the shuttle; a recess in 80 one wall of said passage; a hook extending diagonally across the entrance of said passage and extending forwardly in the direction of the first flight of the shuttle when replenished and downwardly to its point 85 which enters said recess and constituting the engaging means around which the thread reeves as it passes from the weft carrier on the first flight of the replenished shuttle.

3. A left-handed loom shuttle having a threading passage and an eye in the front side of the left-hand end; a guard overhanging the outer end of said passage with its inner edge between the transverse plane of the 95 shuttle eye and the neighboring tip of the shuttle; a wall, and a hook extending diagonally across the entrance of said passage and forwardly in the direction of the first flight of the shuttle when replenished and 100 downwardly to its point and constituting the engaging means around which the thread reeves as it passes from the weft carrier on the first flight of the replenished shuttle.

4. An automatically threading left-handed shuttle having the eye in the front side of the left-hand end and a hook extending across the entrance of its threading passage, said hook extending from one side forwardly in the direction of the first flight of the shuttle when replenished with its upper edge inclined downwardly toward the point, thereby forming a flaring thread entrance between the hook and the opposite wall of 115 said passage, and said hook constituting the engaging means around which the thread reeves as it passes from the weft carrier on the first flight of the replenished shuttle.

5. An automatically threading left-handed 120 shuttle with the eye in the front side and at the left-hand end having a hook extending across its threading passage, said hook extending forwardly in the direction of the first flight of the shuttle when replenished 125 with its upper edge inclined downwardly toward its point, and terminating at its point in a recess in the rear wall of said passage, and said hook constituting the engaging means around which the thread reeves 130

as it passes from the weft carrier on the first flight of the replenished shuttle.

6. An automatically threading left-handed shuttle with the eye in the front side and at 5 the left-hand end having a hook extending across its threading passage, said hook extending forwardly in the direction of the first flight of the shuttle when replenished

with its upper edge inclined downwardly toward its point and constituting the engaging means around which the thread reeves as it passes from the weft carrier on the first flight of the replenished shuttle. 10

In witness whereof, I have hereunto signed my name.

ALONZO E. RHOADES.
